UNITED STATES PATENT OFFICE.

ORVILLE VINCENT DUTRO AND ARTHUR S. BURROUGHS, OF SPOKANE, WASHINGTON.

RECIPROCATING CUTTER FOR PRINTING-PRESSES.

1,372,221.

Specification of Letters Patent.

Patented Mar. 22, 1921.

Application filed April 8, 1919. Serial No. 288,544.

To all whom it may concern:

Be it known that we, ORVILLE V. DUTRO and ARTHUR S. BURROUGHS, citizens of the United States, residing at Spokane, in the 5 county of Spokane and State of Washington, have invented certain new and useful Improvements in Reciprocating Cutters for Printing-Presses, of which the following is a specification.

10 The present invention relates to improvements in reciprocating cutters, and the subject matter of the present invention is particularly designed for use in a printing press of the web feed type in which the web, after 15 being printed, is drawn over proper and suitable rollers, and then the printed web is cut or severed into sheets by the cutter which is operated by the power applied to the action of the printing press, and the 20 cutting device forms one of the units of the combined machine which involves several other features upon which separate applications for patent have been filed in conjunction with this present application.

25 The present invention involves a novel combination and arrangement of the knife or cutter-blade and its construction, and further consists in novel means co-acting with the knife for holding the web or print- 30 ed paper while the knife is performing its function, all as will be pointed out and claimed hereinafter.

In the accompanying drawings one complete example of the physical embodiment 35 of the knife and its appurtenances is disclosed, the parts being constructed and arranged according to the best mode so far devised for the practical application of the principles of the invention.

40 Figure 1 is a side elevation of so much of a machine to which my cutting device has been attached and with which it has been successfully used, as is necessary to illustrate the application thereto of the cutting 45 device.

Fig. 2 is an end view, as seen from the left of Fig. 1, parts being shown in section.

Fig. 3 is a top plan view of the cutter or knife, detached.

50 Fig. 4 is a front elevation of the cutter blade and related parts.

Fig. 5 is a transverse sectional view of the cutter blade and holder, showing also the bed for the cutter or knife blade.

55 The blade or cutter 1 is preferably a sheet

or flexible plate of high grade steel and provided with the beveled and angular, upwardly and inwardly inclined cutting edge 2, and this blade is rigidly attached to the knife bar 3, which is shown as a channel 60 iron of suitable dimensions, spaced from the cutter blade, and located at the rear of the blade. Between the knife bar and the knife are spacers or spacing bushings 4 through which the screws 5 are passed, the screws 65 being arranged in pairs near the ends of the blade and near the top of the blade. Thus the central portion of the blade does not have permanent attachment to the knife bar in same manner that the ends of the blade 70 are attached, but a screw 6 is centrally located near the center of the knife and this screw passes through the blade and is threaded into the knife bar. Thus, in Fig. 3 especially it will be seen that the knife 75 blade is "dished" or cambered horizontally by the utilization of the screw 6, and of course the metal of the blade is resilient to allow for this condition, whereby when the knife blade comes over the die block of 80 knife bed 7, the blade will have a shearing effect thereon and insure a close contact therewith, and the blade will neatly and rapidly sever the web W as the printing press operates.

85 The knife bed B to which die block 7 is removably attached is supported transversely of the frame F of the feeding attachment, and a pair of feed rollers are shown at 8, 8 in Fig. 5 for the web as it passes over 90 the bed 7.

Near its ends the knife bar is provided with a pair of fixed uprights or rods 9, which pass through the channel iron flanges and are secured thereto by nuts 10, and these rods are vertically reciprocable in the bearings 11, secured at the inner sides of the side members of the frame F, to operate the knife blades. The knife bar and knife are thus reciprocable in front of the 100 knife bed and die block and they travel in a path fixed by the movement of the rods 9 in their bearings 11. The rods are connected by links 12 to eccentrics 13 on the eccentric shaft 14, and by the rotation of these eccentrics a vertical reciprocation of the knife is 105 accomplished, the down stroke of the knife being the cutting or shearing stroke, and by a ratchet action on the eccentric shaft the eccentric operation is performed in half a 110

cycle of the press, giving the web a chance to move forward while the knife is still.

In some instances a weight is required in connection with the knife, for holding the web or paper on the knife bed B while the shearing or cutting operation is being accomplished, and preferably this weight is carried and supported by the two uprights or knife rods 9, each of which has a collar 15 fixed thereon. The collars are alined so that they may evenly support the transverse weight bar 16 which has perforations at its ends, as 17, through which the knife rods 9 are passed, and by which the bar is free to move or slide vertically on the rods, or, when the bar is resting on the paper and knife bed, the rods are free to pass through these perforations in the weight bar. The collars are so disposed with relation to the knife bed, that when the knife is in uplifted position, the weight bar is supported on the collars above the knife blade, but upon the down stroke of the knife, the weight bar is deposited on the paper and knife bed and

the knife continues its downward stroke, 25 entering or shearing off the paper after the weight bar has been deposited on the web or paper and knife bed. On the up stroke, the two collars again contact with the weight bar and lift it from the knife bed, the 30 weight bar preventing the paper from catching on the knife and its movement limited to form a guard, and the web which is intermittently moved, is free to be drawn horizontally in Fig. 5 to present another sheet 35 for cutting.

Claim—

The combination with a knife bed, vertically movable knife blade, a knife bar, and guide rods fixed to said bar, of a perforated 40 weight bar loose on the rods, supporting collars on said rods for said bar, and said weight adapted to rest upon said knife bed during the cutting operation of the blade.

In testimony whereof we affix our signatures.

ORVILLE VINCENT DUTRO.
ARTHUR S. BURROUGHS.
